UNITED STATES PATENT OFFICE.

WILBUR L. HOUSEMAN, OF WILMINGTON, DELAWARE, ASSIGNOR TO STANDARD-TRUMP BROTHERS MACHINE COMPANY, OF WILMINGTON, DELAWARE, A CORPORATION OF DELAWARE.

MECHANISM FOR PRODUCING OPENWORK ON KNITTING MACHINES.

Application filed May 1, 1924. Serial No. 710,212.

To all whom it may concern:

Be it known that I, WILBUR L. HOUSEMAN, a citizen of the United States, residing at Wilmington, county of New Castle, 5 and State of Delaware, have invented a new and useful Improvement in Mechanism for Producing Openwork on Knitting Machines, of which the following is a full, clear, and exact description, reference being had to the 10 accompanying drawings, which form a part of this specification:

The production of open-work effect in hosiery by causing certain needles to draw abnormally long loops is well known. It is 15 also known to cause the needles to so operate by means of special sinkers or web-holders provided with stitch-forming elements at different levels. These special sinkers, like the regular sinkers, are movable in and out 20 during the stitch-forming up and down movement of the needles. The extra long loop formed by being drawn over the higher element of the sinker during one course of knitting is, during the next course, drawn 25 over the lower element. Between these two operations, the long loop is more or less robbed of its yarn, thereby reducing its size and temporarily increasing the size of the loops of adjacent wales. By drawing the 30 loop, during the second course, over the lower element of the sinker, the loop is again elongated so as to recover the yarn of which it has been temporarily robbed. The extent to which the loop is again elongated in 35 the second course may be more or less determined by a shoulder above the surface of lower level which engages the bight of the loop during the inward radial movement of the sinker. The proper location of this 40 shoulder will usually involve an undercutting of the metal of the sinker below the higher surface of the sinker, thereby forming an inwardly projecting nose overlying the lower surface and a throat or recess 45 underlying the nose.

When it is desired to discontinue the open-work effect in any particular wale of the fabric, the special sinker is moved out radially beyond its previous outward position and while it is again moved in to co-operate with the needles in the next course of knitting, it is moved in to a less distance, so that the loop is formed initially on the lower surface, whereby the special sinker

performs the function of a regular sinker. 55

The object of the invention is to provide a special sinker adapted to perform the described functions, but which need not be adjusted radially in order to adapt it to operate as a regular sinker. Another object 60 of the invention is to allow the length of the original loop to be varied as desired without the substitution of special sinkers.

In my invention the foregoing objects are accomplished by tilting the special 65 sinker so as to raise the inner or operative end thereof to adapt it to operate as a special sinker, and to lower the inner or operative end thereof so as to adapt it to operate as a regular sinker. In the first 70 described position of the sinker, the yarn, in the inwardly projected position of the sinker, is engaged by the higher stitch-forming surface of the sinker, which (due to the upward tilting of this end of the 75 sinker) is substantially above the level of the yarn-engaging surfaces of the regular sinkers, thereby, in the downward movement of the needle, drawing out a loop of extra length. In the second position of the sinker, 80 the yarn, in the inwardly projected position of the sinker, is engaged, as before, by the higher stitch-forming surface of the sinker. But this higher surface of the sinker (due to the downward tilting of this 85 end of the sinker) is now at or near the level of the yarn-engaging surfaces of the regular sinkers, whereby a loop of normal length is formed. In the first described position of the sinker, the lower surface of the sinker, 90 including the undercut recess described, performs, in the next course, the function of drawing back into the loop the yarn of which it has been partially robbed. In the second described position of the sinker, the 95 lower surface of the sinker is so far depressed below the level of the yarn-engaging surfaces of the regular sinkers that it performs no function.

From the foregoing preliminary description 100 it will be understood that the length of the original loop may be varied, as desired, by tilting up the operative end of the sinker to a variable degree, thereby avoiding the necessity of substituting different sinkers in order to change the lengths of the original loops. It will also be understood 105 that the special sinkers, whether they are

operating to effect the formation of open work or of plain knitting, may occupy the same radial position, which radial position may be the same as that of the regular 5 sinkers; the in-and-out movements of all the sinkers being thereby controllable by a cam which may have as close a sliding fit with all the sinkers as may be desired.

Having described the nature of the invention, I will illustrate its application to a 10 Standard machine such, for example, as is set forth in the Houseman Patent No. 1,207, 757, dated December 12, 1916.

It will be understood, however, that the 15 invention is not limited in its application to any particular type of knitting machine, nor to the specific details of construction illustrated, which are not only capable of variation in a machine of the type illustrated, but 20 which might require special adaptation, within the range of mechanical skill, in the application of the invention to other types of machines.

In the drawings:

25 Fig. 1 is a plan view of the head of a circular knitting machine with my invention applied thereto.

Fig. 2 is a side view of the same, partly 30 in section.

35 Fig. 3 is an enlarged plan view of a part of the needle cylinder (partly broken away to show the slots in which the sinkers slide, and showing also the sinker actuating cams and the lever carrying one of the cams).

40 Fig. 4 is a side view of the said lever and the cam carried thereby.

Fig. 5 is a cross-section through Fig. 4.

45 Fig. 6 is a diagram of a small section of web adapted to be knit by a machine embodying my invention.

Fig. 7 is a diagram showing typical positions occupied by the regular sinkers and special sinkers embodying my invention.

50 Fig. 8 is a diagram of a complete stocking with typical open-work effect produced on a machine embodying my invention.

Figs. 9 to 13 inclusive are detail views of 55 different sinkers in different positions.

55 *a* is the needle cylinder which, in the type of machine mentioned, is rotatable in the formation of the leg and the body of the foot of the stocking and is oscillatable in the formation of the heel and toe portions.

55 *b* is the non-rotatable cam ring carrying the needle actuating cams (not shown). On

60 the stationary sinker cap *p* is a cam *d* for effecting the hereinbefore described movements of inward projection and outward withdrawal of the sinkers. *c* are needles.

x are the regular sinkers or web holders, and *y* and *z* the special sinkers or web holders. See particularly Figs. 9 to 13 inclusive.

65 The regular sinkers *x* may be of any pre-

ferred construction. In Fig. 9, sinker *x* is shown as provided, at its inner end, with a yarn engaging top surface 10 partly overhung by a nose 11 to form a recess 12 into which the yarn of the loop is drawn in the movement of inward projection of the sinker. Near the opposite, or outer, end the sinker is recessed at 13 to receive the cam *d* (see also Figs. 1, 2 and 3), which acts to withdraw the sinker outward before the formation of a stitch and to project it inward at the time of formation of the stitch, in accordance with the usual and well known operation.

The special sinkers *y* are positioned in 80 that half of the needle cylinder carrying the needles which knit the front half of the leg and the top half of the foot. This sinker is provided with two yarn-engaging or stitch-forming surfaces, one an upper 85 surface 20 partly overhung by a nose 21 to form a recess 22, the other a lower surface 23, extending inward substantially beyond the upper surface 20 and partly overhung by the metal forming the front part of the 90 upper surface 20, thereby forming a recess 24. In Fig. 10, the yarn-engaging end of sinker *y* has dropped to its lower position. In this position of the sinker, the upper surface 20 of the sinker is about on a level with the yarn-engaging surface 10 of a regular sinker, and therefore a loop of normal length is formed thereon. If all the special sinkers occupy the position shown in Fig. 10, plain knitting occurs throughout the 100 circumference of the fabric. When, however, the yarn-engaging end of sinker *y* is raised to its higher position, as shown in Fig. 11, the surface 20 of sinker *y* is substantially above the surfaces 10 of the 105 regular sinkers *x* and hence the yarn received on surface 20 is pulled out into an elongated loop. As the needle cylinder continues to rotate, the special sinker *y*, like any 110 of the regular sinkers, is drawn away from the center of the needle cylinder so that the loop formed on its raised surface 20 slips off the front thereof. When the special sinker 20 is, in the next course of knitting, again projected toward the center of the 115 needle cylinder, the previously formed loop (which in the meantime has lost some of its yarn to adjacent wales) is engaged by the lower surface 23 of the sinkers and drawn into the notch or recess 24, thereby 120 again elongating the loop.

The special sinkers *z* are positioned in 125 that half of the needle cylinder carrying the needles which knit the rear half of the leg, the heel, the lower half of the foot, and the toe. The front or yarn-engaging end of sinker *z* is the same as that of sinker *y* and its mode of operation is the same, and therefore the same reference numbers are applied thereto.

Bearing in mind the location of sinkers y in the front half of the needle cylinder and sinkers z in the rear half, it will be understood that, if vertical lines of open-work are to be formed in the stocking, it will be desirable to have such lines extend along both the front and rear of the leg of the stocking and over the top of the foot, as shown in Fig. 8; but it is obviously undesirable to have the open-work effect in the heel, toe, or bottom of the foot. Therefore, provision should be made to move the sinkers z away from the position shown in Fig. 12 just before the leg portion of the stocking is completed and to maintain them out of this position not only during the knitting of the heel and toe, but also during the knitting of the foot portion. During the knitting of the foot portion, it is necessary, in order to produce the described fabric, to maintain the sinkers y in the position shown in Fig. 11. Therefore, it will be understood that while sinkers y and z are, during the knitting of the leg, both in position to form large loops, only the sinkers y are maintained in this position during the knitting of the circular web portion of the foot. Consequently, means must be provided to actuate sinkers y and z at different times. This is effected by so differently shaping the outer ends of the sinkers that both sinkers y and z will be tilted when an actuating cam is moved into one position, while only sinker y will be tilted when the actuating cam is moved into another position, while neither of them will be tilted when such actuating cam is moved into a third position.

It will be observed, by reference to Figs. 10-13, that the rear or outer end of each sinker x and y is bevelled upward toward its rear end (at 26) so as to allow it to be rocked or tilted, that sinker y has an end projection 25 of a certain length, that sinker z has an end projection 35 the front edge of which is in line with the front edge of projection 25, and that projection 35 is of substantially less length than projection 25. The actuating cam e may occupy three positions. When in the position shown in Fig. 10, it engages none of the sinkers and therefore a plain web is knit. In the position shown in Figs. 11 and 13, it engages only the sinkers y and therefore these sinkers alone are moved into position to form the long loops. In the position shown in Fig. 12, cam e engages both sinkers y and z , and both sets of special sinkers are moved into position to form the long loops.

The lower edges of the regular sinkers x are not bevelled at their rear ends and the projections at their rear ends are not high enough to be actuated by the cam e in any of the positions of such cam.

The cam e is secured to a lever f pivoted at g and tending to be retracted by a spring

h . One end of a bell crank lever i is in engagement with the free end of lever f . Lever i may recede to allow the lever f to move to its outermost position, or it may be moved in part way to move lever f into position to project cam e into the position shown in Figs. 11 and 13, or it may be moved in a further distance to move lever f into position to project cam e into the position shown in Fig. 12.

The lever i tends to be held in retracted position by a spring o and is movable into operative position by any suitable pattern mechanism, as by a turnable pattern disc k shown in Figs. 1 and 2. In these figures, the pattern disc is shown provided with a cam having surfaces m and n adapted to tilt the tail of lever i , against the tension of spring o , into position to move lever f to effect the projection of cam e inward to its half way position or to its full inward position. When the cam m , n , entirely overrides the tail of lever i , the cam e is returned to its outer position.

In Figs. 3, 4 and 5, is shown in detail a special means for adjustably securing cam e on lever f . Lever f has a depending flange r slotted to allow the extension therethrough of the shanks of screws s carried by cam e . Cam e is fixed in position by lifting it up against the threaded pins t (held in position by nuts u) and then tightening screws s against flange r . By adjusting the pins t , the vertical position of cam e may be fixed as desired. Thereby the distance to which the tails of the sinkers are depressed may be accurately predetermined, and thus the lengths of the loops drawn thereon may be likewise predetermined.

Fig. 6 illustrates, diagrammatically, a line w of open work such as would be produced by means of a sinker y or z when the front end thereof is elevated as described. Fig. 8 illustrates a stocking containing a number of lines of such open work. In Fig. 7, in order that the described typical arrangement of special sinkers may be understood at a glance, the regular sinkers x have been arbitrarily indicated by fine radial lines, the special sinkers y by heavy solid lines and the special sinkers z by heavy broken lines.

For the sake of presenting the invention in its simplest aspect, I have assumed that the design to be produced comprises a series of vertical stripes of open work extending along the leg of the stocking and along the top of the foot. It will be understood, however, that the invention is not limited to a construction and arrangement of sinkers and actuating mechanism that will produce the particular effect described. Without any change in the sinkers themselves or in any of the actuating means therefor except the cam m , n , the latter may be modified to produce designs other than that described. It will

also be understood that the invention is not limited to any particular number of special sinkers, nor to sinkers shaped precisely as illustrated, nor to the specific mechanism shown for imparting to the forward ends of the sinkers the described bodily movements of elevation and depression.

Having now fully described my invention, what I claim and desire to protect 10 by Letters Patent is:

1. In a knitting machine, the combination with a needle cylinder and a radially movable sinker having at its forward end yarn-engaging elements at different levels, 15 of means to bodily move the forward end of the sinker vertically into a relatively high position to cause the higher and lower yarn-engaging elements to successively act upon the yarn to effect the formation of 20 relatively long loops, and into a relatively low position to allow the higher yarn-engaging element to effect the formation of relatively short loops.
2. In a knitting machine, the combination 25 with the needles thereof and a radially movable sinker having at its forward end two yarn-engaging elements at different levels, of means to bodily move the yarn-engaging end of the sinker to different vertical 30 positions to cause yarn to engage only one of said elements or to successively engage both of said elements.
3. In a knitting machine, the combination 35 with a needle cylinder and a radially movable sinker having at its forward end a yarn-engaging element at a higher level and a more inwardly extending yarn-engaging element at a lower level, of means to bodily move the forward end of the sinker vertically, whereby the forward end of the 40 sinker may lift to cause said element to cooperate to effect the formation of relatively long loops, or sink to allow the higher element to effect the formation of relatively 45 short loops.
4. In a knitting machine, the combination 50 with a needle cylinder, regular sinkers having a yarn-engaging element, and a special sinker having two yarn-engaging elements at different levels, of means to bodily move the forward end of the special sinker vertically into position to bring either of its yarn-engaging elements onto approximately the same level as the yarn-engaging elements of the regular sinkers; 55 whereby in one position of the special
- sinker the higher element thereof will be positioned to effect the drawing of a long loop and the lower element will be positioned to engage the same loop in a subsequent course, while in the other position of the special sinker the higher element will effect the drawing of loops substantially corresponding to those drawn by the yarn-engaging elements of the regular sinkers.
5. In a knitting machine, the combination with a needle cylinder and two radially movable sinkers each having at its forward end a yarn-engaging element at a higher 70 level and a yarn-engaging element at a lower level, of means to effect independent vertical movement of the sinkers so as to cause both of said sinkers to effect the formation of long loops or short loops or one 75 of them to effect the formation of long loops and the other the formation of short loops.
6. In a knitting machine, the combination 80 with a needle cylinder and a radially movable sinker having at its forward end a yarn-engaging element at a higher level and a yarn-engaging element at a lower level, said sinker being rockable so as to swing its inner end up and its outer end 85 down and vice versa, of a cam adapted to engage and depress the outer end of the sinker and thereby rock the sinker to lift its inner yarn-engaging end, and means to move said cam into and out of operative 90 position.
7. In a knitting machine, the combination 95 with the needle cylinder and two radially movable sinkers each having at its forward end a yarn-engaging element at a higher level and a yarn-engaging element at a lower level, said sinkers being rockable to raise or lower their yarn-engaging ends and provided respectively with cam-engaging members of different lengths, of 100 a cam adapted in one position to engage the cam-engaging member of only one sinker and adapted in a different position to engage the cam-engaging elements of both sinkers, and means to move said cam 105 into said two positions and also into position to escape engagement with the cam-engaging members of both sinkers.

In testimony of which invention, I have hereunto set my hand, at Chicago, on this 110 19th day of April, 1924.

WILBUR L. HOUSEMAN.
